UNITED STATES PATENT OFFICE.

JOSEPH LEVY, OF BROOKLYN, NEW YORK.

APPARATUS FOR PERFORATING INSCRIPTIONS, ORNAMENTATIONS, OR THE LIKE ON SHEET MATERIAL.

Application filed March 22, 1928. Serial No. 96,544.

This invention relates to methods and devices for perforating sheet metal and contemplates the provision of an improved apparatus and method for perforating legends, symbols, inscriptions, and ornamentations on sheet metal in making display and ornamental devices such as signs, lamp shades, and the like articles.

One of the objects of the invention is to provide an apparatus of the character described which shall be adapted to perforate flat sheet materials in such manner as to leave the material worked upon substantially flat after the perforation operation has been performed thereon.

Another object of the invention is to provide an improved method for producing articles of the character described, having a simple or intricate perforated legend, inscription, or ornamentation, which shall be simple, easy and comparatively cheap to carry out.

A further object of the invention is to provide an improved perforating apparatus of the character described comprising few and simple parts comparatively cheap to manufacture, easy to manipulate, and practical and efficient in operation to a high degree.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a side elevational view of a perforating machine for carrying out the improved method embodying the invention.

Figs. 2 and 3 are respectively, top plan, and side elevational views thereof.

Figs. 4 and 5 are cross-sectional views taken on lines 4—4 and 5—5 respectively, in Fig. 3.

Fig. 6 is an enlarged cross-sectional view showing in detail the punch and die.

Figs. 7 and 8 are plan views showing a block and script form of sign, respectively.

Fig. 9 is a side elevational view of the sign shown in Fig. 7.

Fig. 10 is an enlarged detail view of a fragmentary portion of the sign shown in Fig. 7 taken along line X—X in said figure.

Referring in detail to the drawing, 10 denotes an apparatus for carrying out the novel sheet perforating method embodying the invention. The apparatus 10 is seen to comprise a bed-frame 11 for suitably supporting a C-shaped punch head 12. The latter has rigidly mounted on the lower jaw 12^a on the front end thereof, a punch die 13. On the upper jaw 12^b of said head there is secured, in any suitable manner as by means of bolts 14, a pair of spaced members 15 which form a slide-way for a vertically movable plunger 16, the latter being adapted to carry a punch 17 on the lower portion 16^a thereof in cooperative alignment with said die 13. Said plunger portion 16^a may be provided with a recess 16^b for receiving the punch 17, said punch being removably secured to said portion 16^a in any well understood manner, as by a clamping set screw 32. The upper portion of said plunger 16 pivotally connects through a knuckle 18 with the lower end 19^a of an adjusting screw 19, the upper end 19^b of said screw being carried by the connecting end 20^a of an eccentric strap 20. The adjusting screw 19 as seen from the drawing, comprises a left and right double ended screw having a head 19^c formed in the mid-portion thereof whereby the said screw 19 may adjust the plunger and punch relative to the eccentric strap 20 so as to set the punch 17 in proper cooperative relation to the die 13. Said eccentric strap may be of any suitable construction and is mounted on an eccentric disc 21 secured to the mid-portion of a drive shaft 22 positioned over the plunger 16. For mounting said shaft, journal bearings 23 are provided on the outer or forwardly extending portion 24^a of a bearing plate 24.

As shown in the drawing, the rear portion 24^b of said plate 24, is pivoted as at 25 to permit limited movement of the plate for raising and lowering of said drive shaft 22 for the purpose hereinafter described. The bearing plate 24 is normally held in a raised position by suitable resilient means, such as compression springs 35, so that the drive shaft 22 and the plunger 16 hold the punch 17 while reciprocating, in a non-cooperative position relative the die 13 to permit the insertion, removal

- and free movement therebetween of a sheet of material 48 to be perforated with a legend, inscription, symbol or ornamentation 49^a. To bring the punch 17 and the die 13 in an effective and cooperative alignment, means for depressing the plate 24 may be provided. Said means are shown in Figs. 1 and 2, and comprise a cam 36 extending over the plate 24 and abutting the upper side of the latter. 10 Said cam has an actuating rock-arm 37 and is trunnioned between a pair of upright supports 38 projecting up from the punch head 12 adjacent the upper jaw 12^b. Swinging the arm 37 clockwise (see Fig. 1) causes the cam 15 36 to depress the plate 24 and is effective to bring the punch 17 in cooperative perforating position to the die 13. An adjustable screw stop 39 may be provided between the plate 24 and the punch head 12 for limiting 20 the downward movement of the plate whereby the relative position of the punch 17 and the die 13 may be adjusted to be most effective, on depressing the plate 24 on said stop 39. Suitable means is provided to operate the cam 36 preferably through the rock arm 37 by the operator's foot so as to leave the operator's hands free for guiding the perforating operation, as will hereinafter appear. Said camming means may include a tension 25 spring 40 secured to the free end of the rock arm 37, the other end of said spring being anchored to a forwardly extending brace 41 mounted on the upper punch jaw 12^b so as to normally retain the arm 37 and cam 36 in position to raise the punch 17 from its effective 30 cooperation with the die 13. Secured to the end of said arm and extending rearwardly there is a flexible cable 42 which passes over sheaves 43, the latter being mounted for rotation on the rear portion of the punch head as 35 shown in Figs. 1 and 3. Said cable 42 extends downwardly and is secured to the mid-portion of a foot lever or treadle 44 which has one end 44^a thereof fulcrumed at 45, so that on depressing the other end 44^b of said treadle, tension 40 is applied to the cable against the action of the spring 40 for rocking the arm 37 to lower the punch 17 into its effective cooperative position with the die 13. 45 A stripper plate 42 through which the punch 17 passes, may be supported from the upper jaw 12^b of the punch head 12 to extend above the die 13 for facilitating the withdrawal of the punch after perforating the 50 sheet 48, in the well understood manner.
- For applying uniform power to the drive shaft 22, a suitable fly wheel 26 may be secured on an overhanging end 22^a of said shaft and suitable driving means and transmission 55 may be provided for rotating said shaft, as for example, the electric motor 27 having a drive pulley 28 which is coupled through a belt 29 to a drive pulley 30, the latter being secured to the other overhanging end 22^b of the drive shaft 22. Said motor may be mount-

ed on a pedestal 31 integrally formed on the rear upper end of the punch head 12 as shown in Figs. 1 and 2.

A work bench top 33 supported by suitable brackets 34 mounted on the lower jaw 12^a of the punch head, may be disposed to extend between the punch jaws, the top portion 13^a of the punch 13 preferably being made to extend through an opening 33^a of said work bench top so that the upper surface thereof is positioned to lie in level alignment with the top surface of the die portion 13^a.

A device D for guiding the operations of perforating the sheet 48 to correspond with a simple or intricately designed pattern such as a legend, symbol, inscription or ornamentation 49 carried on a template or drawing 60, may be mounted on the bench top 33 adjacent the punch and die. Said device may either comprise a pantograph structure of any well understood construction for enlarging or reducing the pattern to be transferred from the template 60 to the sheet 48, or as shown in the drawing, the device D simply provides means for transferring an equivalent facsimile of the pattern. Said device D is adapted to carry the sheet 48 during the perforating operation between the punch 17 and die 13, one edge portion of said sheet being demountably secured to an angle bar 50 of the device D by spaced, wing-screw clamped fittings 57, the outer fitting being provided with a smooth projecting end portion or caster to serve as an anti-friction support for holding the free end 50^a of the angle bar 50 above the table top. The other end 50^b of said bar is carried by a carriage 51 which forms part of said device and rides on another angle bar 52 extending transverse to the bar 50. The carriage 51 may be provided with a pair of spaced rollers 51^a and an intermediate roller 51^b, said rollers being adapted to ride on the opposite surfaces of the upstanding web 52^b of said angle bar 52. The device D also includes a second carriage 53 which may be of similar construction to carriage 51 for carrying the angle bar 52, said carriage 53 having spaced rollers 53^a and an intermediate roller 53^b, the latter rollers being adapted to ride on the upwardly extending web 54^a of a bar 54 which is mounted on the work bench top 33 to extend substantially parallel to the bar 50. The free end 52^a of the angle bar 52 may be provided on the under side thereof with a projecting caster serving as anti-friction bearing for retaining the bar above the work bench surface so as to make said carriages easily movable with respect to each other.

The improved method for perforating the sheet 48 with a legend, inscription, symbol or ornamentation 49^a, will now be described. With the sheet 48 secured in position to the bar 50 as shown in Fig. 2, the template or drawing 60 which has been prepared with the legend or inscription thereon in the desired

configuration is placed on the bench top 33. By means of an indicator 55 having a handle 56 mounted to extend from the carriage 51, said template is positioned to correspond with the length and width of the sheet 48. The movement of the indicator 55 in various directions may be easily made by guiding the handle 56, the carriage 51 permitting transverse movement with respect to the length of the punch head and the carriage 53 permitting movement parallel thereto. The template 60 after being set relative the sheet 48, is preferably secured in position on the table top to prevent accidental movement thereof, and power is then applied to the motor 27 of the apparatus 10 for reciprocating the punch 17. Since the cam and arm are normally in their ineffective position, the punch 17 does not cooperate with the die 13 and the sheet 48 is permitted to be freely moved between the punch and the die without being perforated. The indicator 55 is now guided to outline one of the letters, as for example A. On depression of the treadle 44, the arm 37 and the cam 36 swing the plate 24 down lowering the punch to its cooperative position with the die 13. As the punch 17 is reciprocated with the plunger 16, the indicator is guided to outline the legend or inscription on the template or drawing 60. For efficient operation it has been found that the punch should be about .045 inches in diameter and operated to make from 2,000 to 4,000 strokes per minute. This exceedingly rapid punching with a relatively small die leaves the edges of the legend substantially smooth but of somewhat wavy contour, as shown in a greatly enlarged fragmentary portion of one of such edges, illustrated in Fig. 10, and if desired, these edges may be made smooth by hand filing after the perforating operation is finished.

Where metallic sheets are worked upon it has been found that such sheets can be perforated with any desired legend, inscription or ornamentation, without buckling or bending the sheet so that it leaves the apparatus in substantially the same flat shape as it had at the beginning of the perforating operation, and a dominant feature of the invention resides in the adaptation of the method and apparatus above described, and the arrangement, co-action and control of the various parts thereof to the perforating of comparatively light sheets of metal of various gauges where the maintenance of the flat shape and production of substantially smooth perforated edges is essential in the finished article.

It will be noted that the apparatus and the arrangement of the parts thereof is such as to require comparatively little skill to operate the same or to carry out the method above described in a satisfactory manner. As signs and articles of like character having legends or ornamentations are either of standard form or of special design to serve some spe-

cial purpose, the apparatus and method above described can be employed with the same efficiency and economy either to produce a large number of articles or one or several units of particular specifications, in this way making commercially possible the production of special designed units which have heretofore required either expensive and laborious hand operation of skilled mechanics or expensive specially made dies.

In Fig. 7 the legend comprising the printed letters Ideal, 49^a, is perforated as shown in the blocked-in lines, the perforations being provided only adjacent the edge portions.

In Fig. 8 the inscription shown comprises the script word Beatone, 149^a, which is formed of a single continuous row of perforations.

It will thus be seen that there is provided a device in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. An apparatus of the character described comprising a punch head having a lower and upper jaw, a die mounted on the lower jaw, a punch normally supported for sliding movement on the upper jaw in cooperative relation to said die, eccentric means for reciprocating said punch, said means being pivotally mounted on the punch head, and means for swinging said eccentric means to raise the punch into a non-cooperative position relative to the die while reciprocating the punch to and from the die for permitting the free movement of sheet material between the punch and the die.

2. An apparatus of the character described comprising a punch head having a lower and upper jaw, a die mounted on the lower jaw, a punch normally supported for sliding movement on the upper jaw in cooperative relation to said die, eccentric means for reciprocating said punch, said means being pivotally mounted on the punch head, means for swinging said eccentric means to raise the punch into a non-cooperative position relative to the die while reciprocating the punch to and from the die for permitting the free movement of sheet material between the punch and the die, and foot operated means for returning the reciprocating means to bring the punch and die into normal cooperative relation while the punch is moving to and from the die.

3. An apparatus of the character described for cutting out designs in sheet material to correspond to a given pattern comprising a

punch head including a punch and die, a work bench having the top thereof positioned adjacent the die, eccentric means for reciprocating said punch, a device mounted on the bench including means for carrying sheet material between the punch and the die, means substantially in the same plane with said device for guiding said carrying means to correspond to a template pattern, and 5 means for swinging said eccentric means to move the punch into a non-cooperative position relative to the die.

4. An apparatus of the character described for cutting out designs in sheet material to 15 correspond to a given pattern comprising a punch-head, a punch and die mounted in cooperative relation on said head, a work-bench having the top thereof positioned adjacent the die, said punch being supported on the 20 punch-head for reciprocation to and from the die, eccentric means for positioning the punch in a non-coacting relation to the die while in motion to and from said die, and a device mounted on the bench top having 25 means for carrying sheet material between the punch and the die and means substantially in the same plane with said device for guiding said carrying means to correspond to a template.

30 5. An apparatus of the character described for cutting out designs in sheet material to correspond to a given pattern comprising a C-shaped punch-head having a lower and upper jaw, a die mounted on the lower jaw, 35 a punch normally supported for sliding movement on the upper jaw in cooperative relation to said die, eccentric means for reciprocating said punch, said means being pivotally supported on said punch-head, a work 40 bench having the top thereof substantially level with the top of the die, a device mounted on the bench top including movable means for guiding sheet material between the punch and die and means substantially in the same 45 plane with said device for directing said guiding means to correspond to a pre-determined pattern, means for swinging the reciprocating means to raise the punch into a non-coacting position relative to the die while 50 reciprocating the punch to and from the die for permitting the free movement of the sheet material between the punch and die, and manually operated means for returning the reciprocating means to bring the punch and 55 die into normal cooperative relation with the punch moving to and from the die.

6. In an apparatus of the character described, a punch-head, a punch and die mounted in cooperative relation on said head, 60 said punch normally supported for sliding

movement, eccentric means for reciprocating said punch pivotally mounted for limited movement on the punch head, means for varying said limited movement to regulate the adjustment of the cooperative relation of said punch and die, and means for swinging said eccentric means to raise the punch into a non-coacting position relative to the die while reciprocating the punch to and from the die. 70

7. In an apparatus of the character described, a punch-head, a punch and die mounted in cooperative relation to said head, said punch normally supported for sliding movement, means for reciprocating said punch, a bearing plate having one end thereof pivotally mounted on said punch head, said reciprocating means being mounted on said plate for limited movement therewith, an adjusting screw positioned between the plate and the punch head for regulating the effective coaction of said punch and die, and spring means normally effective to swing said plate for raising the punch into a non-coactive position relative to the die while reciprocating the punch to and from the die. 80

8. In an apparatus of the character described, a punch head, a punch and die mounted in cooperative relation on said head, said punch normally supported for sliding movement, eccentric means for reciprocating said punch pivotally mounted for limited movement on the punch head, and means for swinging said eccentric means to raise the punch into a non-coacting position relative to the die. 90

9. In an apparatus of the character described, a punch head, a punch and die mounted in cooperative relation on said head, said punch normally supported for sliding movement, eccentric means for reciprocating said punch mounted for limited movement on the punch head, and means for swinging said eccentric means to raise the punch into a non-coacting position relative to the die. 100

10. In an apparatus of the character described, a punch head, a punch and die mounted in co-operative relation to said head, said punch normally supported for sliding movement, means for reciprocating said punch, a bearing plate pivotally mounted on said punch head, said reciprocating means being mounted on said plate for movement therewith, and means for moving said plate toward and away from said die whereby said punch and die may be brought into and out of co-acting relation. 110

In testimony whereof I affix my signature.

JOSEPH LEVY.
